Frederic A. Jenks, Rockville Centre, Thomas M. Ferrill, Jr., Hempstead, and Donald F. Folland, East Hempstead, N. Y., assignors to Sperry Gyroscope Company, Inc., Brooklyn, N. Y., a corporation of New York

Application November 7, 1942, Serial No. 108,717

Term of patent 7 years

To all whom it may concern:

Be it known that we, Frederic A. Jenks, Thomas M. Ferrill, Jr., and Donald F. Folland, citizens of the United States of America, residing at, respectively, Rockville Centre, Hempstead, and East Hempstead, all in the county of Nassau and State of New York, have invented a new, original, and ornamental Design for an Aircraft Landing Instrument Indicator, of which the following is a specification, reference being had to the accompanying drawing, forming part thereof.

Fig. 1 is a front elevational view and Fig. 2 is a sectional view taken on line 2—2, in Fig. 1 of an aircraft landing instrument indicator, showing our new design.

We claim:

The ornamental design for an aircraft landing instrument indicator, as shown.

FREDERIC A. JENKS.
THOMAS M. FERRILL, JR.
DONALD F. FOLLAND.
